(57) **CLAIM**

The ornamental design for a “support bracket”, as shown and described.

DESCRIPTION

FIG. 1 is a isometric view of a support bracket;

FIG. 2 is a front view of the design of FIG. 1;

FIG. 3 is a side view of the design of FIG. 1; and,

FIG. 4 is a top view of the design of FIG. 1.

Any broken lines in the drawings depict probable environment only and form no part of the claimed design.
